DESIGN FOR A LINK CHAIN FOR A BRACELET OR SIMILAR ARTICLE

Georg E. Lederman, New York, N. Y., assignor of one-half to Jack L. Shaw, New York, N. Y.

Application November 8, 1944, Serial No. 116,209

Term of patent 3½ years

(Cl. D45—16)

To all whom it may concern:

Be it known that I, Georg E. Lederman, a citizen of Poland, residing at New York, county of New York, and State of New York, have invented a new, original, and ornamental Design for a Link Chain for a Bracelet or Similar Article, of which the following is a specification, reference being had to the accompanying drawing, forming a part thereof.

Fig. 1 is a top plan view of a link chain showing my new design;

Fig. 2 is a side view thereof;

Fig. 3 is a perspective view of two adjacent elements of the link chain.

I claim:

The ornamental design for a link chain for a bracelet or similar article, as shown.

GEORG E. LEDERMAN.
